UNITED STATES PATENT OFFICE.

CHARLES H. GUNN, OF OAKLAND, CALIFORNIA.

EXTENSION-TABLE.

1,378,375.

Specification of Letters Patent. Patented May 17, 1921.

Application filed June 14, 1920. Serial No. 388,740.

To all whom it may concern:

Be it known that I, CHARLES H. GUNN, a citizen of the United States, residing at Oakland, in the county of Alameda, State 5 of California, have invented certain new and useful Improvements in Extension-Tables; and I do declare the following to be a full, clear, and exact description of the same, reference being had to the accompanying drawings and to the characters of 10 reference marked thereon, which form a part of this application.

This invention relates to improvements in extension tables, and particularly over 15 that form shown in my co-pending application for patent Serial No. 386,051, filed June 2nd, 1920.

The principal object of the present invention is to provide an extension table, 20 such as are used in dining rooms to normally accommodate a relatively few people but which may be extended to take care of a considerable number, which may be extended to give a plurality of different sizes 25 and in which the added area is had by means of permanently mounted leaves, which do not have to be removed from the table when it is desired to close or contract the table, or vice-versa.

Another object is to so arrange the extension features relative to the main supporting frame and legs, that the latter maintain a permanent spacing, as the frame and legs are not pulled apart as is customary with 30 most extension tables, and which is a weak feature thereon, since the central portion becomes a weak member when extended, there being no rigid and permanent central framework.

A further object is to provide a table of this character which may be easily set in its various positions without the necessity of lifting any weights to any marked degree, as must be done with the ordinary 40 removable leaves.

Another object of the invention is to produce a simple and inexpensive device, and yet one which will be exceedingly effective for the purposes for which it is 45 designed.

These objects I accomplish by means of such structure and relative arrangement of

parts as will fully appear by a perusal of the following specification and claims.

In the drawings similar characters of 55 reference indicate corresponding parts in the several views.

Figure 1 is a side elevation of the table, closed.

Fig. 2 is a longitudinal section of the 60 same, fully extended.

Fig. 3 is a similar section of the table, partly extended.

Fig. 4 is a cross section of the table.

Referring now more particularly to the 65 characters of reference on the drawings, the numeral 1 denotes a pair of side boards or frames, 2 transverse end frames of a lesser height than the members 1 but terminating at the same bottom level, and 3 the supporting legs, positioned at the junction of the side and end boards.

A central and permanent table top 4 is supported on the side boards and extends transversely thereof, these frames, legs and 75 top forming a rigid and fixed unit.

At each end of the top 4 are relatively narrow leaves 5, connected by beams 6 extending under the top 4 and projecting somewhat beyond the ends of the leaves 5. 80

The beams 6 are spaced far enough from the corresponding side frames 1 to leave room for a pair of guide members 7 on each side and therebetween, these guides being pivoted on a common rod 8 extending between the boards 1.

In corresponding pairs of the guides 7 slide bars 9, extending in opposite directions beyond the leaves 5, and each such pair of bars is connected at their outer ends 90 by transverse end boards 10.

A leaf 11 is hinged to each board 10, as shown at 12 which, when the bars are pulled out to their fullest extent, also rest on the projecting ends of the beams 6 and 95 are then flush with the leaves 5.

To govern and limit the movement allowed the guides 9, the under side of the latter are notched where necessary as shown at 13 which notches engage the inner edge 100 of the cross beams 2 of the main frame, the guides 9 passing thereover and resting thereon.

In order to give the leaves 5 a vertical

movement equal to the thickness of the tops 4 and 11, which are of course the same, the beams 6 rest on cams 14 eccentrically mounted on the rod 8 and arranged to give 5 the necessary amount of movement.

These cams are connected to a cross bar 15 to which is flexibly connected the inner end of an operating arm 16 which projects beyond one of the end beams 2 through 10 a slot 17 therein, the arm 16 being notched at a certain point as at 18 to engage the beam 2, and having a spring 19 bearing thereon to maintain the notch in engagement with said beam, this being when the 15 cams are moved to raise the leaves 5.

The outer end of the arm 16 is provided with a handle 20 or similar means whereby it may be grasped and pulled by the hand.

In the closed position of the table, as 20 shown in Fig. 1, the outer leaves 11 rest on the permanent center top 4 and abut against each other. In this position the intermediate leaves 5 are depressed so that the leaves 11 pass thereover in spaced relation thereto. In order to present a neat appearance, the leaves 11 are provided with edgings 21 on their under sides, which rest on the leaves 5, and abut against the top 4. Also this top 4, is provided with similar 25 under-side edgings 22, which align with the leaves 5 when the latter are depressed. In this manner a stepped appearance is avoided when the table is closed up, which of course is its normal and mostly used position. If 30 it is desired to extend the table to the position shown in Fig. 3, that is partially extended, the leaves 5 are not disturbed, and the outer leaves 11 are pulled away from each other until their ends are adjacent the 35 ends of the top 4, when they will drop into position on the leaves 5, one set of notches in the slides 9 then engaging the end beams 2 to prevent further movement. It will be noted that the beams 9 rest at all 40 times on the beams 2 and are also held against upward movement at their inner ends by the slides 7, while the flexible or pivoted mounting of the latter permits the raising or lowering of the leaves 11 the 45 necessary distance without manual effort.

When it is desired to extend the table to its full limit, the slides 9 are raised from their notched engagement with the beams 2 and pulled still farther out, which lowers 50 them at the same time, since the said slides are angled relative to the plane of the various leaves. When moved out to their limit, there is then just room for the leaves 5 between the top 4 and leaves 11, and the said 55 leaves 5 are then raised by pulling the cam-operating arm 16, which turns the cams and forces the leaves 5 up to the level of the top 4. The supporting beams 6 thereof projecting beyond the ends of the leaves, said 60 beams engage the under sides of the 65

leaves 11, and also bring them up to and hold them at the level of the leaves 5, and all parts are then in a common horizontal plane.

In this position, the beams 6 bear against 70 the under side of the top 4, which precludes the possibility of the leaves 5 tipping at one end or the other on the cams which support them.

From the foregoing description it will be 75 readily seen that I have produced such a device as substantially fulfills the object of the invention as set forth herein.

While this specification sets forth in detail the present and preferred construction of 80 the device still in practice such deviations from such detail may be resorted to as do not form a departure from the spirit of the invention, as defined by the appended claims.

Having thus described my invention what 85 I claim as new and useful and desire to secure by Letters Patent is:—

1. An extension table comprising a supporting frame, a central table top fixed thereto, intermediate leaves at the ends of 90 the central top and normally depressed relative thereto, means for raising the intermediate leaves to the level of the central top, and outer end leaves normally overlapping the central and intermediate leaves and 95 adapted to be pulled away from each other for certain predetermined distances.

2. An extension table comprising a supporting frame, a central table top fixed thereto, intermediate leaves at the ends of 100 the central top and normally depressed relative thereto, outer end leaves adapted to overlap the central top and to be moved to abut against the ends of the top and also beyond the plane of the intermediate leaves, 105 and means for then raising the latter to the level of the top.

3. An extension table comprising a supporting frame, a central table top fixed thereto, intermediate leaves at the ends of 110 the central top and normally depressed relative thereto, outer end leaves adapted to overlap the central top and to be moved to abut against the ends of the top and also beyond the plane of the intermediate leaves, 115 and a common hand actuated means whereby the latter may then be raised to the level of the top.

4. An extension table comprising a supporting frame, a central table top fixed 120 thereto, intermediate leaves at the ends of the central top and normally depressed relative thereto, outer end leaves adapted to overlap the central top, means whereby such leaves may be moved apart certain predetermined distances and then lay in the horizontal plane of the central member, and means for raising the intermediate leaves to the level of the central top when the outer leaves are pulled to their limit of movement. 130

5. An extension table comprising a supporting frame, a central table top fixed thereto, intermediate leaves at the ends of the central top and normally depressed relative thereto, but adapted to be raised to the level thereof at will, guide members pivotally mounted in pairs under the top transversely thereof, bars slidable in corresponding guides, each pair projecting independ-

ently of the other beyond opposite ends of 10 the top, and a leaf hinged to the outer end of each pair of slidable bars, such bars being adapted for horizontal movement to position the leaves carried thereby at predetermined distances apart. 15

In testimony whereof I affix my signature.

CHARLES H. GUNN.
